FIG. 5. 7 → 6

FIG. 6.

FIG. 7.

FIG. 8.

FIG. 9.

FIG. 1 is a perspective view of the top, front and right side of a camper vehicle showing my new design;

FIG. 2 is a perspective view of the top, rear and left side thereof;

FIG. 3 is a perspective view of the top, front and right side of a camper vehicle showing a second embodiment of my new design;

FIG. 4 is a perspective view of the top, rear and left side thereof;

FIG. 5 is a top plan view of the living compartment section of the camper vehicle, with the bed in folded position and the table and bench back cushions in seating position;

FIG. 6 is an interior perspective view thereof taken along the line 6-6 and looking in the direction of the arrows;

FIG. 7 is an interior perspective view thereof taken along the line 7-7 and looking in the direction of the arrows;

FIG. 8 is a fragmentary top plan view thereof with the table lowered and the bed unfolded in sleeping position; and

FIG. 9 is an interior perspective view thereof taken along a line similar to line 6-6.

The characteristic features of the present design reside in the interior portions of the vehicle as best shown in FIGS. 5 through 9.

This application is a continuation-in-part of my application Ser. No. D. 25,605, filed Oct. 22, 1970, and now abandoned.

I claim:

The ornamental design for a camper vehicle, as shown and described.
